(57) CLAIM

I claim the ornamental design for a bottle, as shown and described.

DESCRIPTION

FIG. 1 is a side elevation view of a bottle, showing the present invention, the opposite side view being identical except for the unclaimed threads.

FIG. 2 is a bottom plan view thereof; and,

FIG. 3 is a top plan view thereof.

The broken lines shown in the drawings are for illustrative purposes only and form no part of the claimed design.
